PHOTOGRAPHIC COMPOSING DEVICE
Bernard Borisof, Chicago, Ill., assignor, by mesne assignments, to Friden, Inc., San Leandro, Calif., a corporation of Delaware
Filed Sept. 5, 1961, Ser. No. 136,060
7 Claims. (Cl. 95—4.5)

This invention relates to a photographic composing device and more particularly to an improved means for justifying lines of copy.

In photographic composing devices of the type employing the contact printing principle, column justifying for advertisement make-up copy is quite complicated. For the method most commonly used, the space required for words, numerals, characters and descriptive phrases must first be computed for the type font and point size of type to be used in a predetermined column width. Thereafter, the device is adjusted for each line, in accordance with the computation, to justify each margin in a given column width so that the words, numerals, characters and phrases will appear in neat columns within the predetermined width.

Another method for justifying the left and right margins for any column width is to "dry run" a line or actually "set" a line which is then developed and measured to ascertain the position of the photosensitive paper for the beginning and ending of each line. For example, in setting a column for a grocery advertisement, the starting position of the paper must be noted so that the first letter in each line will be in vertical alignment, justifying the left margin. Similarly, the movement of the paper must be ended in the same position for each line to justify the right margin, thereby effecting the formation of neat columns of words and numerals. Equally important is the position of the print paper for the quantity column and also the quantity descriptive column when setting each line. In present practice, each of these print paper positions is determined by counting the unit movement of the paper during a print operation, and failure to do so, or a miscalculation, will cause poor column structure.

It is, therefore, an object of the present invention to provide a simple means for easily and quickly setting up advertising copy.

Another object of the present invention is to provide a gauge which may be removably secured in place to justify the left and right margins for any type font and point size numeral or letter in a desired column width.

A further object of the present invention is to provide a device for use in a photographic composing machine operable to enable the composition of columns of numerals or other characters automatically one below another.

Another object of the present invention is to provide a gauge for a photographic composing machine operable to enable the photographic printing of a series of lines of composition or dotted lines one below another to a predetermined length.

Other objects and advantages will become apparent from the following description of a preferred embodiment as illustrated in the accompanying drawings, in which:

FIG. 1 is a transverse sectional elevational view of the photographic composing device, as viewed from the rear.

FIG. 2 is a detailed showing of the control means for effecting contact printing.

FIG. 3 is a plan view of the justifier gauge in place on the discharge chute of the photographic composing device.

FIG. 4 is an end view of the discharge chute with the justifier gauge in place thereon, the view being taken on the plane indicated by line 4—4 in FIG. 3.

2

FIG. 5 is a fragmentary sectional plan view of the composer with a portion of the carriage broken away to show the carriage adjustment mechanism, the view being taken on the plane indicated by the line 5—5 in FIG. 1.

FIG. 6 is a diagrammatic showing, in perspective, of the film control mechanism and the wiring schematic therefor.

FIG. 7 is an enlarged view of the height gauge for indicating the adjusted position of the composer carriage.

FIG. 8 is a full scale three-line copy of a justified setup using 36-point characters.

FIG. 9 is a full scale three-line copy of a justified setup using 24-point characters.

FIGS. 10 and 11 are full scale copies of printed strips showing, respectively, 36-point and 24-point capital letters, lower case letters, punctuation marks and leader dots printed from a retailer film font.

FIG. 12 is a full scale printed strip showing of the 24-point and 36-point numerals carried on a retailer film font.

FIG. 13 is a full scale printed strip showing of the 36-point characters and the descriptive matter appearing on a retailer film font.

The invention is preferably shown as being used in combination with a photographic composing device of the type utilizing a film strip, which is movable into printing contact with a photosensitive paper strip and is, thereafter, manipulated to effect movement of the paper strip and the exposure of a selected character.

In the embodiment shown, the photocamera comprises base portion 10 (FIG. 1) and the carriage 12 pivotally supported on the base portion along one side thereof by means of the shaft 14. To support the carriage 12, shaft 14 is journaled at its rearward end in bracket 15 (FIG. 5), integrally formed on base 10, and at its forward end, the reduced end portion 16 of the shaft 14 extends through a suitable aperture in the front wall 17 of the base portion 10 and carries the circular knob 18 secured thereon. Similarly, shaft 14 is journaled in each of a pair of brackets 19 and 20 (FIGS. 1 and 5) integrally formed on carriage 12. While brackets 19 and 20 serve to pivotally support carriage 12 on shaft 14, bracket 19 also serves as a means for enabling movement of the carriage 12 forwardly and rearwardly. For this purpose, bracket 19 is provided with internal threads which are engaged with threads 21 on the shaft 14 adjacent the forward end thereof. Following the assembly of shaft 14 in the base portion 10, the shoulder formed by the reduced diametral end portion 16 of the shaft is maintained against the inner surface of the front wall 17 of the base by means of screw plug 22 which is threaded into bracket 15 to prevent endwise movement of the shaft. Thus, clockwise or counter-clockwise rotation of the knob 18 serves to adjust the carriage 12 forwardly or rearwardly, respectively, relative to the base 10 by virtue of the engagement of the threads 21 on shaft 14 with the threaded bracket 19 of the carriage.

The opaque photographic film strip 26, having transparent letters, numerals, punctuation marks and descriptive words and phrases appearing thereon, is suitably supported for longitudinal movement within carriage 12. One end of the film strip 26 is received and wound on reel 27 supported for rotation on the shaft of motor 28, while the other end of the film is received and wound on reel 29 supported for rotation on the shaft of motor 30 (FIGS. 1 and 6). The motors 28 and 30 are mounted in spaced and substantially coplanar relationship on the carriage 12 with the axes of rotation of the motors being substantially parallel one with the other. As determined by its winding and construction, the normal rotation of motor 28 is in a counter-clockwise direction, while that

of motor 30 is in a clockwise direction so that, upon energization of either motor 28 or 30, the film strip 26 may be moved rapidly to the left or right, respectively.

In its course of travel between reels 27 and 29, the film strip 26 passes over tapered rolls 31 and 32 in frictional contact with sleeves 33 and 34 (FIG. 6), preferably of rubber, secured thereon. Rolls 31 and 32 are secured on one end of respective shafts 35 and 36 which are suitably journaled in the base portion 10 and have divergent axes in a plane parallel to the plane of the axes of rotation of the reels 27 and 29. The angle of divergency of shafts 35 and 36 is equal to the included angle of either tapered roll 31 or 32. Thus, the film 26 is parallel with the surface of the sleeves 33 and 34 at substantially the point of tangency of the film with the sleeves in its path of travel from the respective reels 27 and 29. At its other end, each of shafts 35 and 36 is provided with a bevelled gear connection 37 and 38, respectively, with shaft 39, which is suitably supported in carriage 12. One end of the shaft 39 extends outwardly through the wall of the carriage to provide a support for wheel crank 40, which is secured thereon.

Movement of the film strip 26 to the right or left (FIG. 6) may be controlled by clockwise or counter-clockwise rotation, respectively, of wheel crank 40. In its movement to the right or left, film 26 passes beneath, and in contact with, pressure plate 44 (FIG. 1) having a slot-like aperture 45 therein, disposed transversely of the path of travel of the film and in register with the exposure aperture 46 in the lower wall of exposure lamp compartment 47 in carriage 12. In order to maintain film 26 in proper exposure relationship to the aperture 45 in plate 44, each of a pair of similar guide strips 48 is secured to the lower surface of the lamp compartment 47, equally spaced either side of the aperture and in parallel relationship to each other and to the aperture.

As stated above, upon energization of either motor 28 or 30, rapid movement of the film 26 in either direction is selectively controlled. When desirable, the film strip 26 may be moved slowly in either direction by manipulation of wheel crank 40 to control the precise movement of the film and a selected character thereon relative to the exposure aperture 45. However, to manually control the movement of the film 26, the film must be maintained in a taut condition for frictional engagement with rubber sleeves 33 and 34 on respective rolls 31 and 32. For this purpose, motors 28 and 30 are preferably of the series-wound type having their field and armature windings connected in series relationship and are of substantially equal size with equal ratings and torque characteristics. The motors 28 and 30 are connected in series through a lead 52 (FIG. 6) and are connected with power supply lines 53 and 54 by means of lead 55 connecting motor 28 with power supply line 53 and by lead 56, switch 57 and lead 58 connecting motor 30 with power line 54. Thus, upon closure of switch 57, normal operating voltage for each motor is reduced to half of its rated voltage. Inasmuch as the direction of rotation of one motor is opposite that of the other motor, the torque developed by one counteracts the torque developed by the other, so that each is maintained in a stalled condition, keeping the film 26 under tension.

Either of the motors 28 or 30 may be energized in a manner such that substantially full line voltage is supplied to a particular motor, thereby effecting rapid movement of the film strip 26 in a direction determined by the motor which has been energized. For this purpose, a single-pole double-throw switch is provided, having a movable contact 59 and stationary contacts 60 and 61 (FIG. 6). Movable contact 59 is connected to the series line connection 52 between motors 28 and 30, while stationary contact 60 is connected to power supply line 54 through line 62, line 58, switch 57 in line 56, and stationary contact 61 is connected by means of line 63 to power supply line 53. Following closure of switch 57 and the engage-

ment of the movable contact 59 with stationary contact 60, motor 30 is substantially short-circuited and full line voltage is supplied to the motor 28, thereby causing movement of the film 26 to the left, as viewed in FIG. 6. Likewise, when contact 59 engages contact 61, motor 28 is substantially short-circuited and the full line voltage is supplied to the motor 30 to move film 26 toward the right.

The foregoing description, it is believed, will suffice 10 for an understanding of the mechanism for controlling movement of the film strip. However, for a more complete description, reference is to be had to my copending application Serial No. 45,465, filed July 26, 1960 and entitled "System and Apparatus for Feeding and Positioning a Web," which application is now abandoned.

During operation of the composing device, the selected 15 transparent letters, numerals, or characters, carried by the opaque film strip 26, as seen in FIG. 5, are photographically reproduced individually by the contact printing 20 process on the photosensitive paper strip 68 (FIG. 1), which feeds from a suitable light-proof pack (not shown) through chute 69, passes over backing roller 70 and is discharged through chute 71. Roller 70 is rotatably 25 mounted on shaft 72, suitably supported in base portion 10 with its axis parallel to the lower surface of plate 44 and disposed transversely of the path of the film 26, corresponding to the lengthwise disposition of exposure aperture 45. For each selected letter, numeral or character 30 to be reproduced on the print paper 63, the area of the film bearing the desired letter is moved into exposure 35 position relative to aperture 45 and the carriage 12 is lowered by manipulation of arm 80 so that the film 26 and print paper 63 are compressed between plate 44 and backing roller 70. The exposure lamp is then turned on and 40 wheel crank 40 is rotated to move film 26 to the right, as viewed in FIG. 1, which, due to the frictional contact 45 of the film with the print paper 63, also causes paper 63 to move to the right through the discharge chute 71. During this movement, the selected letter, numeral, or character 50 is reproduced on the sensitized paper strip 68. The exposure lamp is then extinguished and the carriage 12 is raised to enable movement of the film strip independently of the paper strip, either manually under control of crank 40 or by selective operation of motors 28 or 30, to correctly position the next desired letter, numeral, or character relative to exposure aperture 45. The extent of movement of film strip 26 and paper strip 68 for each exposure is determined, in a conventional manner, by the utilization of starting target 73 and ending target 74 (FIG. 5) for each letter.

Briefly, a transparent plate 77, preferably of a synthetic 55 resin, such as Lucite, is adjustably mounted within the base portion 10 and is disposed in a plane parallel to the plane of the path of travel of the film strip 26 (Fig. 5) with the film passing thereover. Engraved in black on the top surface of the plate 77 is a starting line 75 extending at a right angle to the lower edge of the film strip, as viewed in Fig. 5, and a diagonal ending line 76. Lengthwise adjustment of the plate 77 transversely of the film strip 26, by conventional means not shown herein, controls the normal spacing between the letters or characters of each font of type selected for use. As the plate 77 is moved upwardly or downwardly in Fig. 5, the spacing between the lines 75 and 76 becomes narrower or broader at the target area on the film strip 26. The target area of the film is the lower edge portion thereof which is transparent and along which the letters or characters are indicated, disposed between the starting target 73 and the ending target 74 therefor.

Following the adjustment of the plate 77, the starting 70 target 73 for a selected letter or character is positioned on the starting line 75, the carriage 12 is dropped to engage the film strip 26 with the photosensitive strip 68 and the exposure lamp is turned on. By manipulation of crank 40, the film strip and photosensitive strip are then moved

together (to the left in Fig. 5) until the ending target 74 for the selected letter has just passed beyond the starting line 75. Whereupon, the exposure lamp is turned off and the film strip and photosensitive strip are returned to the right to position the ending target 74 on the ending line 76. The return of the carriage 12 to its raised position is then effected to enable the selection of the next letter or character to be reproduced.

It will be noted that any adjustment of the plate 77 (Fig. 5) upwardly or downwardly from a normal setting for a particular font of type will increase or decrease the spacing between letters.

Normally, the carriage 12 is retained by cam 78 in the raised position shown (Figs. 1 and 2), wherein the film strip 26 is out of contact with the photosensitive strip 68. Cam 78 is positioned on the inside of one end wall of carriage 12 and is secured on one end of shaft 79, the other end of which extends through the wall of the carriage having arm 80 secured thereon. To lower the carriage 12, arm 80 is rocked clockwise (Fig. 2) against the urgency of the relatively strong spring 81, moving the high point of the cam 78 out of engagement with the top surface 82 of the wall of base 10, thereby permitting the carriage to rock downwardly of its own weight about shaft 14 sufficiently to move film 26 into printing contact with the strip 68. Arm 80 is manually held in its vertical position until the exposure of the selected letter is completed, whereupon the arm is released to the urgency of the spring 81, coming to rest on stop pin 83, and the cam 78 restores the carriage to the normally raised position shown.

A plurality of lines of copy may be composed, one below another, on the photosensitive strip and the location of each line and spacing between lines is controlled by the adjustment of the carriage 12 and the edgewise displacement of the film strip 26 relative to the photosensitive strip 68, in accordance with the point size of the characters to be printed. For this purpose, height gauge 86 is provided (Figs. 5 and 7) secured at its one end on, and at a right angle to, the offset extension 87 of arm 88, which is welded or otherwise secured on the sleeve 89, freely mounted on shaft 14 and prevented from endwise movement thereon by means of clips 90. Arm 88 extends laterally of sleeve 89 beneath the web portion 91 of the carriage 12 with the offset portion disposed in the elongated slot 92 (Figs. 1 and 5) in the web portion 91 and the offset extension 87 resting upon the top surface of the web. The gauge 86, representative of the width and defining the path of travel of the photosensitive strip 68, extends transversely of, and beneath, film strip 26 and lies in a plane parallel to the plane of movement of the film strip. One-half the width of the gauge 86 is marked or engraved to indicate point graduations, while the other half is graduated in increments of an inch. Inasmuch as the gauge 86 remains stationary, film strip 26 is moved relative thereto by rotation of the circular knob 18 (Fig. 5) and the adjustment, therefore, of the carriage 12 forwardly and rearwardly. The location of each line of copy on the photosensitive paper 68 is determined by observing the relationship of a letter of the selected type font on the film strip 26 with the height gauge 86, as indicated by the letter "K" shown in phantom line in Fig. 7.

In the preparation of a plurality of lines of advertising copy, it becomes necessary for neat copy that the left and right margins be justified in a predetermined column width. As stated hereinbefore, during an operation of the composing device, the photosensitive paper strip 68 passes over backing roller 70 and is discharged through chute 71 (Fig. 1). In order to prevent exposure of the discharged portion of the paper strip and the loss of the latent images thereon, a sleeve, generally indicated at 96 (Figs. 1, 3 and 4), is removably secured on the outlet end of the discharge chute 71, which in cross-section, is substantially rectangular in shape. Thus, upon leaving the discharge chute 71, the photosensitive paper 68 moves

along within the sleeve 96 until the line of copy is completed, whereupon the paper strip is severed by operation of a conventional cutter 97. The exposed portion of the paper strip is then removed from the sleeve for the subsequent development process.

Sleeve 96 comprises a substantially rectangular plate 98 riveted or otherwise secured along each respective lengthwise edge portion thereof on one leg of each of a pair of similar elongated U-shaped members 99 having an opposed spaced parallel relationship one to the other. The internal width between the web portions of the U-shaped members 99, as well as the width of the opening of the U-shaped members, is sufficiently greater than the width and depth of the outlet end portion of the discharge chute 71 to enable the engagement of one end of the sleeve 96 over the outlet end of the chute 71 and to removably retain the sleeve in position thereon. Preferably, the plate 98 is of a red translucent thermoplastic material, but may be made of any material which will tend to filter out the ambient actinic light to prevent further exposure of the paper strip 68 as it passes therebeneath and will be sufficiently transparent to visually follow the movement of the paper strip as it passes through the sleeve 96. To visually determine the extent of movement of the photosensitive paper 68 in the sleeve 96, a scale 100, preferably graduated in inches in one-sixteenth increments, is engraved in the top surface of the plate 98 extending longitudinally thereof and midway of the area between the ends of the flanges of the respective U-shaped members 99. It will be understood that the scale 100 may be graduated in any of various increments and in any form of linear measure. With the use of the scale 100, it becomes extremely easy to quickly ascertain the length of line copy which is being composed. Before the actual exposure of each letter, numeral or character making up the line copy is initiated, carriage 12 is lowered and with the exposure lamp extinguished, crank 40 is rotated to feed the end of the paper strip 68 into the sleeve 96 to the "0" graduation on the scale 100. Thereafter, the exposure of each letter or character is effected sequentially and the length of the copy line is determined by the end of the paper strip 68 upon reaching the predetermined graduation on the scale 100.

In composing lines of copy for advertisements, in which a selected point size of one of various type fonts is to be used, the left and right margin justification for any predetermined column width may be easily accomplished with the use of a justifier gauge, generally indicated at 101 in FIGS. 3 and 4. Gauge 101 is in the form of a channel member 102, the upper flange of which (FIG. 4) is offset intermediate its width providing a wider opening, equivalent to the thickness of the sleeve 96. The flanges of the channel member are formed inwardly toward each other and the internal dimension of the opening at their outer extremity is slightly less than the thickness of the sleeve 96. Also, the material of which the channel member is made is sufficiently flexible to enable the flanges to be forced outwardly, so that the gauge may be installed and resiliently maintained in any set position on the sleeve 96. The narrow portion 103 of the channel member 102 provides a hand grip for removably positioning the gauge 101 on the sleeve 96.

In the embodiment shown, the justifier gauge 101 is illustrated for use in the composition of grocery advertising copy and the type font utilized is depicted in FIGS. 10, 11, 12 and 13. The 36-point and 24-point capital letters, lower case letters, punctuation marks and leader dots are illustrated, respectively, in FIGS. 10 and 11, while the 24-point and 36-point numerals are illustrated in FIG. 12. Also included in the particular type font chosen for illustration are the 36-point characters and the descriptive words shown in FIG. 13.

In order to use the justifier gauge 101, the columnized template 104 for the particular point size of the desired type font to be used is secured by an adhesive, or other

suitable means, to the top surface of the offset portion of the channel member 102 overlying plate 98 of sleeve 96. If a plural line copy of 36-point letters, leader dots, numerals and characters is to be composed, in accordance with the sample showing illustrated in FIG. 8, the 36-point mark 105 on template 104 is aligned with the graduation on the scale 100 corresponding to the column width desired. Knob 18 is then rotated to adjust the carriage 12, moving the film strip 26 relative to the sensitized paper 68 in accordance with a predetermined graduation on height gauge 86 for the first copy line. Following the adjustment of the carriage 12, the end of the sensitized paper 68 is moved out to the "0" designated mark on the scale 100, which, thereafter, becomes the starting position for each line of copy. The composition then begins with the photographic reproduction of the name of the article in a manner such as that described hereinbefore and for each letter of the word the end of the tape moves along the scale 100 in the sleeve 96. Following the completion of the reproduction of the word, the printing of the leader dots begins in a manner similar to the printing of the letters of the word and continues until the end of the sensitized paper 68 reaches the 36-point mark 105 on template 104. It will be noted, that although there are but three leader dots indicated on the portions of the reproductions shown in FIGS. 10 and 11, an adequate predetermined number of equally spaced dots is provided on the film strip 26 to enable a continuous reproduction of dots as the photosensitive paper is moved by the film strip to the desired point on the template 104. Also, if the leader dots are not desired, the photosensitive paper 68 may be moved along, with the exposure lamp off, until the end of the paper is aligned with mark 106. Thence, the end of the paper 68 is moved from mark 106 to the mark 107 on template 104 as the quantity numeral is printed thereon, followed by the movement of the end of the paper to the mark 108, during which time the descriptive word or phrase is reproduced. Paper strip 68 continues to be moved by film strip 26 as the value of the article is printed, whereupon the end of the strip arrives at the 36-point line 105, thereby completing the first line of copy.

For the second line of copy, the position of the carriage 12 is adjusted by manipulation of knob 18 (FIG. 5) in accordance with a predetermined reference point on height gauge 86 so that the next line of copy will be substantially centered transversely of the paper strip 68. The carriage 12 is then lowered by manipulation of arm 30 (FIG. 2) and with the exposure lamp extinguished, the paper strip 68 is restored to its initial starting position wherein the end of the paper strip is aligned with the "0" marking on scale 100 (FIG. 3). Thereafter, the printing of the second line of copy is carried out in a manner similar to that described above, followed by a similar procedure for the photographic reproduction of the third line of copy, after adjustment of the carriage 12 to correctly position the film strip 26 with reference to the lowest graduation on gauge 86.

In order to justify the left and right margins of a plurality of lines of copy using 24-point letters, numerals and characters similar to the reproduction shown in FIG. 9, the justifier gauge 101 (FIG. 3) is positioned on sleeve 96 so that 24-point mark 109 is aligned with the desired column width graduation on scale 100. Following the positioning of the justified gauge, the end of the photosensitive paper strip 68 is moved into position relative to the "0" mark on scale 100 and the printing of the line of copy proceeds in the manner similar to that described above, except that the printing of the leader dots, following the name of the article, is terminated as the end of the paper strip 68 reaches the 24-point mark 110 on gauge 101. Also, upon completion of each line of copy, the end of the paper strip will be aligned with the 24-point mark 109.

Regardless of the point size of type selected for use, the

numerals, characters and phrases will be confined automatically within the defined areas therefor indicated on template 104. In order to ensure such confinement in the embodiment of the invention shown and described herein, the operating width of each 24-point numeral, i.e., the distance between the starting target 73 and ending target 74 therefore is equivalent to the distance between marks 110 and 107 on template 104. Similarly, the operating width of each 36-point numeral is equivalent to the spacing between marks 106 and 107 on template 104. The operating width of all 24-point characters is identical as is the operating width of all 36-point characters, so that the combined widths of two 24-point numerals and a character will invariably equal the spacing between marks 103 and 109 on template 104. Likewise, the combined widths of the two 36-point numerals and a character is equivalent to the spacing between marks 108 and 105. As for the phrases, the operating width of all phrases is identical for either the 24-point or 36-point type and this width is equal to the spacing between marks 107 and 108 on template 104.

It will be understood that the invention is not to be limited to the embodiment shown but may be utilized to justify any columnized advertising copy using various type fonts and point sizes of type. A template for the particular form of advertisement desired is removably secured on the justifier gauge 101.

I claim:

30 1. A photographic composing device comprising a light source, means for moving an opaque film strip and a photosensitive strip in superposed relationship past said light source, said film strip having a plurality of transparent characters formed thereon for photographic reproduction on said photosensitive strip during operation of said moving means, means for shifting said film strip edgewise transversely of the photosensitive strip to enable the reproduction of each of a plurality of lines of composition, and a gauge disposed transversely of the path of travel of said film strip and said photosensitive strip delineated to represent the invariable path of travel of said photosensitive strip and positioned for passage of said film strip thereover, said gauge for determining the position of each line of composition relative to the edges of said photosensitive strip upon operation of said shifting means.

50 2. A photographic composing device comprising a print strip upon which a plurality of lines of copy may be photographically reproduced, an opaque film strip in superposed relationship to said print strip and having a series of spaced transparent characters formed thereon, a light source, a pair of film reels disposed on opposite sides of said light source for supporting the respective ends of said film strip so that said film strip may be fed from either reel to the other reel past said light source, means for enabling operation of either of said reels to move said film strip in either direction, means for urging said film strip into photographic contact with said print strip so that upon operation of said enabling means said print strip will be caused to move with said film strip to effect an exposure of selected characters forming a line of copy, adjusting means for positioning said film strip in each of a plurality of positions relative to said print strip to enable the sequential printing of a plurality of lines of copy, a discharge sleeve into which the exposed portion of said print strip is directed during operation of said enabling means in one direction subsequent to the operation of said urging means, said discharge sleeve including a graduated scale, and a justifying gauge selectively settable on said discharge sleeve in accordance with a predetermined column width as determined by said scale, said gauge providing a starting position and terminating position for said printed strip during the exposure of the characters forming each line of copy thereby justifying each margin for a predetermined column width.

3. In apparatus of the character described in claim 2, wherein said discharge sleeve is of a transparent actinic light filtering material for enabling a visual check of the movement of the print strip.

4. A photographic composing device comprising a light source, means for feeding an opaque film strip and a photosensitive strip in superposed relationship past said light source, said film strip having a series of transparent characters formed thereon for reproduction on said photosensitive strip to form a line of selective groups of characters during operation of said feeding means, means for directing the exposed portion of said photosensitive strip exteriorly of said device during operation of said feeding means, means for adjusting said film strip relative to said photosensitive strip to enable the reproduction of a plurality of lines of the selective groups of characters in columnar form, a transparent sleeve secured on said directing means for guiding the photosensitive strip in its movement exteriorly of said device, a scale graduated in increments of linear measure from a "0" point of beginning inscribed on said sleeve for visually determining the extent of movement of the photosensitive strip in said sleeve, a gauge settable in a selected one of a plurality of positions on said sleeve relative to said scale, and a series of spaced index marks on said gauge, one of said marks for indicating the setting of said gauge by the registry of said one of said marks with a selected graduation on said scale to predetermine the length of the exposed portion of said photosensitive strip, the spacing between adjacent ones of the other of said marks being effective to represent invariable limits for the movement of said photosensitive strip during the sequential exposure of selected groups of characters in each line thereby effecting reproduction of the groups of characters in columnar relationship.

5. In a photographic composing machine having a light source, means for moving an opaque film strip in either direction past said light source, said film strip having a plurality of transparent characters formed thereon and being engageable in a superposed relationship with a photosensitive strip for movement of the photosensitive strip therewith past said light source, a first fixed index point on said machine and a first index mark on said film strip adapted to register therewith to indicate the starting position for movement of the film strip and photosensitive strip in one direction past said light source for the exposure of a particular character, a second fixed index point on said machine and a second index mark on said film strip adapted to register therewith to indicate the ending position of the film strip and photosensitive strip in movement past said light source to complete exposure of the particular character, the distance between said first index mark and said second index mark for each character being equal, means for engaging said film strip with said photosensitive strip so that said photosensitive strip will be caused to move with said film strip upon operation of said moving means, means for controlling said light source to extinguish the light upon movement of said film strip and said photosensitive strip in the other direction, means for shifting said film strip transversely of said photosensitive strip for each of a plurality of lines of exposed characters, means direction the exposed portion of said photosensitive strip exteriorly of the machine during operation of said moving means subsequent to the operation of said engaging means, and means for effecting a plurality of columns of exposed characters, the combination comprising a guide means for directing the exposed portion of said photosensitive strip in its path of travel from said directing means, a scale on said guide means graduated in increments of linear measure from a point of beginning in register with which the leading end of the photosensitive strip is positioned for the beginning of each line of characters to be composed by the operation of said engaging means and subsequent operation of said moving means, a gauge adjustably slidable on said guide means relative

to said scale, and a series of spaced indicator marks on said gauge, one said indicator mark indicating the terminating point for the leading end of the photosensitive strip during its movement by said moving means for each line of composition and positionable by adjustment of said gauge for registry with a selected graduation on said scale to predetermine the length of each line of composition, each pair of adjacent marks of the other of said indicator marks being spaced equal to the spacing between the said first index mark and said second index mark for at least one character on said film strip whereby the leading end of the photosensitive strip will invariably move from one said indicator mark to the adjacent indicator mark for the exposure of one or more characters in accordance with the spacing between the indicator marks and for each line of composition to effect columnization of the characters.

6. A photographic composing device comprising a print strip upon which a plurality of lines of copy may be 20 photographically reproduced in a columnar arrangement, an opaque film strip in superposed relationship to said print strip and having a series of spaced transparent type characters of each of a plurality of point sizes formed thereon, a light source, means for urging said film strip 25 into photographic contact with said print strip, means for enabling movement of said film strip in each direction past said light source independent of said print strip and operable subsequent to the operation of said urging means to move said print strip with said film strip in one direction 30 from a starting position for the exposure of selected characters forming a line of copy and in the other direction to the starting position upon completion of each line of copy, means for controlling the operation of said light source during the movement of said print strip in either direction by said enabling means, means for moving 35 said film strip to each of a plurality of positions relative to said print strip and transversely of the path of travel of said print strip for the photographic printing of each line of copy, a transparent actinic light filtering sleeve mounted 40 on said device into which the exposed portion of said print strip is visually directed during operation of said enabling means, scale of inches and equal increments thereof from "0" inscribed on said sleeve representative of a selective column width, and a justifier gauge settable on said sleeve relative to said scale operable to 45 represent the starting position and terminating position for the movement of said print strip during operation of said enabling means thereby predetermining the length of each line of copy for columnization of material in accordance with a selected one of a plurality of point sizes 50 of characters, said gauge including indicia thereon representative of the area limit for the exposure of the characters in each line in accordance with the setting of said gauge on said sleeve.

55 7. A photographic composing device comprising a light source, means for moving an opaque film strip and a photosensitive strip in superposed relationship past said light source, said film strip having a plurality of transparent characters formed thereon for photographic reproduction on said photosensitive strip during operation of said moving means, means for shifting said film strip edgewise transversely of the photosensitive strip to enable the reproduction of each of a plurality of lines of composition, 60 a gauge disposed transversely of the path of travel of said film strip and said photosensitive strip adjacent said film strip for movement of said film strip thereover, said gauge being delineated to represent the invariable path of travel of said photosensitive strip and the position of said film strip relative to said photosensitive strip to determine the 65 position of each line of composition upon operation of said shifting means, means for directing the exposed portion of said photosensitive strip exteriorly of said device during operation of said moving means, means for directing the exposed portion of said photosensitive strip exteriorly of said device during operation of said moving means, means including 70 a scale aligned with said directing means for movement 75 a scale aligned with said directing means for movement

of the photosensitive strip therealong and operable to control a predetermined length of the exposed portion of said photosensitive strip for each line of composition, and a justifying gauge selectively settable relative to said scale representative of a predetermined column width, said gauge being delineated to control the position of said photosensitive strip for the reproduction of each of a plurality of characters in a columnar relationship in a plurality of lines of composition subsequent to each operation of said shifting means.

UNITED STATES PATENT OFFICE
CERTIFICATE OF CORRECTION

Patent No. 3,183,812

May 18, 1965

Bernard Borisof

It is hereby certified that error appears in the above numbered patent requiring correction and that the said Letters Patent should read as corrected below.

Column 2, lines 60 and 61, for "descriptive" read --
descriptive --; column 3, line 51, for "connectd" read --
connected --; column 7, line 63, after "that" insert -- the --;
line 65, for "justified" read -- justifier --; column 8, line
7, for "therefore" read -- therefor --; line 42, after "gauge"
insert -- having graduations thereon --; column 9, line 16,
strike out "the"; column 10, line 26, for "each" read --
either --; line 42, after "means," insert -- a --; same column
10, line 55, for "phosographic" read -- photographic --.

Signed and sealed this 5th day of October 1965.
